UNITED STATES PATENT OFFICE

CHARLES M. LISH, OF VALPARAISO, INDIANA

HIGHWAY RAILROAD CROSSING

Application filed October 8, 1928. Serial No. 310,984.

My invention relates to improvements in highway railroad crossings and it more especially consists of the features pointed out in the claims.

5 The purpose of my invention is to provide corrugated metallic units formed in duplicate for use between the rails; to provide duplicate units for use outside of the rails; to overcome the slippiness of all metal treads 10 for highway crossings; to combine narrow metallic portions extending crosswise of the highway with alternate parallel portions of concrete or other roadway material; to provide for the easy installation of the metallic units at highway crossings, on bridges, etc.; to produce a form of crossing which can 15 be easily manufactured at small cost; and to provide a crossing that is almost indestructible.

20 With these and other ends in view I illustrate in the accompanying drawing such instances of adaptation as will disclose the broad underlying features of my invention without limiting myself to the specific details 25 shown thereon and described herein.

Figure 1 is an elevation in section of a highway railroad crossing.

Fig. 2 is an elevation in section of the invention applied to a bridge girder.

30 Fig. 3 is an enlarged detail elevation of the left hand end of Fig. 1.

Fig. 4 shows a modification of Fig. 3 showing duplicate sections on each side of the track rails.

35 Fig. 5 is an elevation in section showing shallow grooves formed in the upper or street surface portions of my metallic railroad grade crossing.

Fig. 6 is a further modification of Fig. 3.

40 Fig. 7 is an elevation in longitudinal section showing fastening means applied at the ends of the corrugated units.

Fig. 8 is an elevation in section of a pair of replaceable units.

45 In practically carrying out my invention, I may use whatever alternative forms of construction that the exigencies of traffic and other conditions may demand without departing from the broad spirit of the invention.

50 All sorts of expedients, metallic and other-

wise, have been proposed to make railroad grade crossings easy to negotiate, and to insure a long life of the materials that are used to fill in the space between the track rails of the railway and also to form the approaches 55 on each side of the railway line. Slabs of concrete, ordinary wooden planks and flat metallic plates have been proposed, and in instances used. With concrete slabs there is a rapid deterioration of the adjacent upper 60 corners of the slabs. Wooden planks have a notoriously short life aside from their slippiness and tendency to curl in hot weather.

All-metal plates have been found unsatisfactory because of their slick upper surface 65 which is not entirely overcome even though rivet heads are placed here and there. There is a further disadvantage in the use of metallic units placed only on each side of the track rails, the space between the inner sections 70 being filled with ordinary paving materials.

With my invention I overcome these difficulties by forming a metal sheet into deep duplicate corrugations, each corrugation approximating a rectangular shape in cross 75 section. The upper or street surface portion of the corrugation unites the vertical portions and these in turn are united by a base portion through which any desired fastening means may pass for holding the corrugated 80 units on the ties. The corrugations which open upwards are filled with any desired material which has a more or less rough surface. Concrete or any substitute may be used.

85 Instead of placing fastening means through the lower portion of the corrugation separate fastening plates may be used at the outer ends of the units, as shown in Fig. 8. The latter expedient will be found very 90 serviceable whenever the road bed, ties, etc., require attention, for in such an event completed corrugated units, shown in Fig. 8, may be bodily removed while the repairs are being made, and thereafter replaced.

95 The individual units may contain whatever number of corrugations are found to be expedient. If desired the end fastening plates may have an upstanding projection, as shown in the right hand portion of Fig. 8. 100

These projections separately close the open ends of each upwardly facing corrugation and they serve to hold the concrete or whatever filling material is used in place while it is setting. When these plates are fastened to the ties they will securely hold the units in place and yet they are readily removable.

The individual units, shown in Fig. 8, may be formed as duplicates of each other for the mid portion of a railroad grade crossing or a bridge pavement, or the units may be made in duplicate to serve for the approach portion of a crossing and as separate units for the inner side of the railway rails.

15 Standard interchangeable units comprise vertical portions 5 joined at the top by portions 11 and at the bottom by portions 6. The outside edge of each unit is formed of a single vertical portion 5 that may be joined at the top to another vertical portion 5 or joined at the bottom, as the case may be. Into the upwardly facing corrugations concrete or other material 10 is placed. The units may rest on ties 9 or any other support such as bridge girders 20. The plates 25 may be held by fastening nails 8 or otherwise, and if desired, the plates 25 may have upwardly extending projections 26, wide enough so that a single one will approximately close 25 the open end of a corrugation into which the paving material 10 is placed.

In case it is desired to install the units in a relative permanent manner the expedient shown in Fig. 1 may be followed. In this instance two duplicate units are shown between the track rails which are secured to the ties by spikes or nails 8, or otherwise. Where these units meet bottom flanges 12 may be formed as shown in Fig. 1 and the portion of 35 each unit adjacent the inner edge of the rails may be formed with a reverse vertical bend 13, a short horizontal bend 14 to pass under the rail head 1, and a reverse vertical bend 15 adapted to lie adjacent the web 3 of the rail between its base 2 and the head 1.

40 In Fig. 1 the approach units are shown in duplicate. These consist of outside fastening flanges 12, the usual base portion 6, vertical portions 5 joined by a tread portion 4. The tread portions 4 and 11 may have slight grooves 21 formed lengthwise thereof, as shown in Fig. 5; and the portion 7 of the unit adjoining the outside of the rail may be formed at an angle, as shown in Figs. 1 and 3. 45 This portion will rest upon the base 2 of the rail adjacent the rail web 3. The units placed adjacent the inner edge of the rails form a wheel flange clearance 16.

The structure instanced in Fig. 3 may be 50 modified, as shown in Figs. 4 and 6. In Fig. 4 the units for both edges of the rail may be duplicates of each other. They comprise tread portions 11, base portions 6, vertical portions 5, a narrow horizontal portion 22, a 55 short vertical portion 23, a diagonal portion

17 positioned under the rail head 1, a vertical portion 18 positioned adjacent the rail web 3, and a diagonal portion 19 resting on the rail base 2. This diagonal portion 19 may abut the vertical portion 5 so as to hold the vertical portions 5 and 18 in spaced apart relation. In the case of Fig. 6, the tread portion 11 is joined to a short vertical portion 23, a diagonal portion 24 with a reverse bend onto itself and a horizontal portion 14 which 60 engages the web of the rail just below the head.

From the description it will be seen that my invention broadly comprises forming a sheet material into deep corrugations of a given number and filling the corrugations on one side of the sheet with a paving material, and in suitably holding the so formed units in position in any cooperative manner for railroad grade crossings or bridges or for general paving purposes.

I do not of course limit myself to the sides of the corrugations being in parallel relation to each other as it is obvious that they may be formed at a slight angle to each other so as to form slightly undercut portions to assist in holding the paving material, shown in the left hand portion of Fig. 7.

Should it be desired to close the end openings of all the corrugations at one time a beveled plate 27 shown at the left hand side of Fig. 8 may be used. It has flanges 28 and 29 which may rest on a tie 9. In connection with the outside flange 28 nails or spikes may be used to fasten it to the tie and the inside flange or foot 29 may be positioned beneath the units with which it is assembled. The purpose of beveled ends, whether formed of sheet metal or wood or otherwise is to safeguard the units when used for railroad grade crossings against damage should any part of a train become loosened and drag along the ties. The beveled plates 27 will cause any dragging part to ride over the units without damage.

110 What I claim is:

1. A composite highway material comprising a metallic sheet formed into relatively deep corrugations having tread and base portions uniting them, a support for the base portions positioned at points throughout their length, and a suitable paving material positioned in the corrugations on one side of the sheet.

2. A composite highway paving material comprising a sheet formed into corrugations having relatively flat upper and lower connecting portions, and a suitable paving material in the corrugations.

3. A new article of manufacture comprising a sheet formed into relatively deep corrugations of a given number to constitute a unit, a similar unit having cooperating edges, and a plastic self-hardening material placed in

the corrugations approximately to their full depth.

4. A composite unit comprising a resilient metallic sheet formed into adjacent corrugations the edges of each unit being formed with walls that cooperate with the edges of other similar units, and a filling material in the corrugations.

5. A composite highway paving material comprising a sheet formed into corrugations and a suitable paving material placed between the side walls of the upper corrugations and terminating approximately on the same plane as the upper portions of such corrugations.

10 6. A composite unit formed of a corrugated sheet having a given number of corrugations one edge of the unit adapted to cooperate with an edge of a similar unit, the other edge adapted to engage the sides of a railroad rail with the corrugations approximately parallel to the rail, and means for holding one or more units in cooperative relation with each other against accidental displacement.

20 7. A railway-highway crossing comprising a resilient metallic sheet formed into adjacent corrugations running approximately parallel to the rails of the crossing said corrugations having relatively flat upper and lower connecting portions the corrugations being approximately the height of the rails, a support for the flat lower portions of the corrugations, and a suitable paving material in the corrugations.

25 8. A new article of manufacture comprising a sheet formed into adjacent corrugations, a railway rail, edges of the sheet cooperating with the web and base portions of the rail the first corrugation adjacent the head of the rail being spaced apart from the rail head with the corrugations running approximately parallel to the rail, a suitable paving material in the upwardly opening corrugations, and means for supporting such a corrugated unit in operative relation adjacent the rail against displacement.

30 9. A new article of manufacture comprising a sheet formed into relatively deep corrugations and adapted through the formation of its edges to position itself against either side of a railway rail while leaving a space between the first corrugation and the head of the rail to form a clearance for the flanges of traversing car wheels, and a suitable paving material in the corrugations as desired.

35 10. A composite highway paving material comprising a sheet formed into corrugations having grooved upper portions and relatively flat lower portions, and a suitable paving material in the corrugations.

In testimony whereof I affix my signature.
CHARLES M. LISH.
